UNITED STATES PATENT OFFICE.

ALEXANDER MICLAUS, JR., OF ALLIANCE, OHIO.

GUN-MOUNT.

1,142,602.

Specification of Letters Patent. Patented June 8, 1915.

Application filed April 5, 1915. Serial No. 19,212.

To all whom it may concern:

Be it known that I, ALEXANDER MICLAUS, Jr., a subject of the King of Roumania, residing at Alliance, in the county of Stark 5 and State of Ohio, have invented certain new and useful Improvements in Gun-Mounts; and I do hereby declare the following to be a full, clear, and exact description of the invention, such as will enable others 10 skilled in the art to which it appertains to make and use the same.

My present invention relates to improvements in gun mounts for light guns, and it is especially intended to provide a light 15 portable mount which may be carried attached to or separate from the gun, and quickly applied to the gun or to the means of support.

In modern warfare the facility with which 20 the munitions of war may be transported from place to place and set up for use, or removed when desired, is a very important factor, and is often a determining factor in a battle, or even in a campaign, and this invention is intended to especially provide a light portable gun-mount adapted to be used in connection with light artillery, and especially with mitrailleuse, or other light 25 automatic guns of similar caliber and high 30 speed of firing.

My invention is especially intended to provide a mount for the gun described and claimed in my application entitled Improvements in automatic guns, filed December 2, 35 1914, Serial No. 875146, and many of the details of the mount shown in the present application are described in my application aforesaid.

My invention will be understood by reference to the accompanying drawings in which:—

Figure 1 shows a central vertical section through the lower portion of the mount, but the upper portion of the mount being shown 45 in elevation and the gun being shown in dotted lines, the section being along the lines 1—1 of Fig. 7, and 7—7 of Fig. 6, looking in the direction of the arrows; Fig. 2 is a view showing the upper portion of the mount of Fig. 1 on a larger scale; Fig. 3 is a plan 50 view of the laterally adjustable carriage used for transporting the gun and mount, parts being broken away; Fig. 4 shows a section along the line 4—4 of Fig. 3, looking 55 in the direction of the arrows, parts being

shown in elevation; Fig. 5 is a detail showing the engagement of the toggle arms of the carriage shown in Fig. 3; Fig. 6 is a side elevation of the socket piece used in transporting the mount on the carriage or chamber used as a standard for firing the gun from a boat or other fixed platform; Fig. 7 shows a section along the line 7—7 of Fig. 6, and looking in the direction of the arrows, parts being shown in elevation; Fig. 8 shows the tripod and gun mount swung up parallel to the barrel of the gun for convenience of packing same either on an animal, or in a boat or other conveyance; Fig. 9 shows a section along the line 9—9 of Fig. 2, looking down, parts being shown in elevation; and Fig. 10 is a detail view showing the operation of the catch for holding the worm spindle, and worm, out of engagement.

The gun 1 may be of any suitable type, preferably a light automatic gun of the character shown in my application aforesaid, which gun is indicated in dotted lines in Figs. 1, 2 and 8. Rigidly connected to the gun is a supporting block 2, provided at its heel with a worm sector 3. The supporting block 2 is connected by the pivot bolt 4 to the side plates 5 of the yoke 6, which side plates are rigidly attached to the circular base plate 7 which is provided with a downwardly-projecting stem 8, notched as at 9, which stem is adapted to be swiveled in the auxiliary support for the mount, as will be hereinafter more fully described. The side plates 5 of the yoke are cut away as at 10 to give clearance for the worm 11 mounted on the spindle 12, which spindle carries the hand wheel 13 for turning the worm and elevating and depressing the gun. This hand wheel 13 may be provided with a handle 14 if desired. The worm spindle 12 is reduced near its forward end, as at 15, and passes through the cylindrical bearing block 16, which is journaled in the side plates 5 of the yoke 6 so as to permit the worm spindle to swing in the vertical plane about the axis of said bearing block 16, and the worm spindle is held against being drawn out of said bearing block 16 by means of a suitable collar 17 and pin 18. This collar may be in the form of a rectangular plate, if desired, as shown in Figs. 2 and 9, so as to permit the worm spindle 12 to be swung in a vertical plane, and tends to steady the same against lateral vibration.

The worm spindle 12 engages in a yoke 19 normally pressed upward by the spring 20, to hold the worm 11 in the position for engaging the worm sector 3, as shown in Figs. 5 1, 2 and 8.

To permit holding the worm 11 out of engagement with the worm sector 3, when desired, I provide a catch 21^a on the heel 21 of the yoke 19, which engages the stop 23, 10 fast to one or both of the plates 5, when the spindle 12 is swung downward about its pivot block 16; this shoulder 21^a is snapped into engagement by the spring plunger 22, as shown most clearly in Fig. 15 10. For convenience in releasing the catch 21^a when desired, a push button or knob 25 may be attached to the heel 21 of the yoke 19, whereby said heel may be pushed inward against the action of the spring plunger 22, thus releasing the catch 21^a and permitting the spring 20 to restore the worm spindle, and worm, to the engaging position.

It will be seen that by turning the hand wheel 13, when the worm and worm sector 25 are in engagement, the gun will be elevated or depressed. The gun may be trained laterally by swinging the breech of the gun laterally by hand in the usual way, or suitable training gear, not shown, may be used 30 if desired. There are a great many kinds of training gear known in the art which could be used in connection with my invention, and I do not claim any specific means for training the gun in azimuth.

35 In order to clamp the gun at the desired position laterally, I provide a lug 30 projecting downward from the base plate 7 and provided with a clamp screw 31 which engages the head of the tripod mount, as will 40 be hereinafter more fully described.

The gun when being fired is preferably mounted on a tripod mount such as is shown in Figs. 1, 8 and 9, in which the head of the tripod is provided with a housing 40 perforated as at 41 to receive the pivot bolt or stem 8 of the mount, which stem is preferably held in said housing, but free to turn therein by means of the set collar 42. This housing 40 is provided with three downwardly-projecting ribs 43, to which the tripod legs 44 are hinged as shown most clearly in Figs. 1 and 8. The tripod legs 44 are preferably made of hollow steel and terminate in the shoes 45 and spikes 46.

55 Mounted in the tripod legs 44 are the spring impressed catches 47, see Fig. 8, each of which is normally pressed outward by the spring 48 engaging the collar 49, and the end of the catch engages in the toothed segment 50. These catches 47 may be automatically withdrawn by means of the levers 51, see Fig. 8, whose inner ends engage the collar 49, and when the outer end 52 of said lever is pressed upward the collar 49 is drawn back, releasing the catch from the

segment and permitting the tripod legs to be swung outward or inward, whereby the height of the gun above the ground may be varied at will. When the lever is released the spring 48 will automatically restore the 70 catch to the engaging position.

For purposes of transportation or for convenience of storage in wagons, railroad cars, or the like, the tripod legs may be swung toward each other and the tripod may be 75 swung to the position substantially parallel to the barrel of the gun, as shown in Fig. 8, at which time the gun and mount will take up very little space either in the car, wagon, boat or the like. For convenience of transportation in the field, I provide an auxiliary support adapted to be 80 temporarily mounted on a carriage especially constructed for the purposes that will be hereinafter described.

85 Referring to Figs. 1, 6 and 7, 60 represents a socket piece in the form of a hollow cylinder adapted to receive the stem 8 and provided with a spring-impressed catch 61 adapted to engage the annular notch 9 of the stem 8. This spring-impressed catch is normally held in engagement by the spring 62 engaging its outer end 63, and by pressing on this end against the action of said spring 62 the catch may be released when 90 desired. To limit the inward movement of the head of the catch 61, when the stem 8 is not in place, one or more side lugs 64 are provided which engage the outer face of the cylinder 60 at the sides of the slot 100 in which the catch 61 is pivotally mounted. The lower end of this cylinder 60 is preferably screw-threaded, as at 65, to engage in corresponding screw threads 70 provided in the eye 71 of the trail piece 72, see Fig. 3: 105

This trail piece is provided at its forward end with a T 73; and at its rear end a suitable drag bar 74, or other suitable means for dragging the same is provided. The trail is also provided with a series of perforations 75 to engage the locking pin 76, which may be any ordinary pin, but preferably a spring-impressed pin such as is shown in Fig. 4, in which this pin 76 is provided with a collar 77 normally pressed downward by the spring 78 mounted in the spring box 79 carried by the cross head 80. The upper end of this pin 76 is provided with a hand knob 81 by means of which the said pin may be conveniently lifted against the action of said spring. To the T 73 at the forward end of the trail are pivoted two connecting rods 82, and the opposite ends of these connecting rods 82 are pivoted, as at 83, in the hub block 84 on which the wheels 110 85 are journaled. The outer ends of these connecting rods 82 are provided with gear segments 86 intermeshing with corresponding gear segments 86^a, see Fig. 3, on the contiguous connecting rods 82^a whose inner 115 120 125 130

ends are pivoted to the cross head 80 which slides on the trail 72. By sliding the cross head 80 backward or forward on the trail, the connecting rods 82 and 82^a serve as a toggle joint to bring the wheels closer together, as indicated in dotted lines in Fig. 3, or to move them farther apart as shown in full lines in said figure. Thus the carriage is laterally collapsible and may be used to 10 run on a narrow trail, when desired, or spread out to run on a wide road. Moreover, by bringing the wheels as close together as practicable the carriage takes up very little space in transportation by rail. 15 wagon, or boat, and may be conveniently hidden or concealed when not in use.

It will be noted that for use in a boat or moving platform it may be desirable to mount the cylinder 60 in any suitable step 20 and fire the gun as from a standard mount, and in this case the tripod legs may be either left in place or not used, or may be removed from their housing, or the entire tripod arrangement may be taken off the stem 8, and 25 the amount used directly on the standard as desired.

Wherever practicable, the parts are made of hollow light metal of great rigidity and strength, such, for instance, as vanadium 30 steel.

Thus it will be seen that I have provided a light portable mount which may be readily transported either attached to or separate from the gun; and may be quickly mounted 35 on its transporting carriage, or detached therefrom; and which may be quickly put into use either on the tripod mount or on a standard mount. It will also be seen that I provide a collapsible carriage to be used 40 in connection with the mount aforesaid, which is suited to run through narrow passes, or trails, in forests or elsewhere, or narrow roads generally, and the gage of which may be expanded or contracted as desired. 45

While I have illustrated and described one embodiment of the invention it will be obvious that various modifications might be made in the device and in the construction, 50 combination and arrangement of parts which could be used without departing from the spirit of my invention.

Having thus described my invention what I claim and desire to secure by Letters Patent of the United States is:-

1. The combination with the gun and a supporting member rigidly attached thereto, and provided with worm teeth, of a yoke hinged to said supporting member and provided with a worm adapted to engage said worm teeth and to be thrown out of engagement therewith if desired, and means for supporting said yoke, substantially as described. 30

2. The combination with the gun and a

supporting member rigidly attached thereto, and provided with worm teeth, of a yoke hinged to said supporting member and provided with a worm adapted to engage said worm teeth and to be thrown out of engagement therewith if desired, a pivot bolt projecting downwardly from said yoke, and means for supporting said pivot bolt, substantially as described. 70

3. The combination with the gun, of a downwardly-projecting supporting member carried by said gun and provided with a segmental rack having worm teeth, a yoke pivoted to said segmental rack, and provided with a downwardly-projecting pivot bolt, 80 means for supporting said pivot bolt, and a worm journaled in said yoke and adapted to engage said worm teeth, with means for throwing said worm into and out of engagement with said worm teeth, when desired, substantially as described. 85

4. The combination with the gun and a supporting member rigidly attached thereto, and provided with worm teeth, of a yoke hinged to said supporting member and provided with a worm adapted to engage said worm teeth and to be thrown out of engagement therewith if desired, a pivot bolt projecting downwardly from said yoke, and a 90 socket piece for supporting said pivot bolt, 95 substantially as described.

5. The combination with the gun, of a downwardly-projecting supporting member carried by said gun and provided with a segmental rack having worm teeth, a yoke pivoted to said segmental rack, and provided with a downwardly-projecting pivot bolt, a socket piece for supporting said pivot bolt, and a worm journaled in said yoke and 100 adapted to engage said worm teeth, with means for throwing said worm into and out of engagement with said worm teeth when desired, substantially as described. 105

6. The combination with the gun and a supporting member rigidly attached thereto, 110 and provided with worm teeth, of a yoke hinged to said supporting member and provided with a worm adapted to engage said worm teeth and to be thrown out of engagement therewith if desired, a pivot bolt projecting downwardly from said yoke, and a tripod provided with a housing engaging said pivot bolt, and having legs adjustably hinged to said housing, substantially as described. 115

7. In a gun of the character described, the combination with the gun, of a downwardly-projecting supporting member carried by the receiver and provided with a segmental rack having worm teeth, a yoke pivoted to 125 said segmental rack, and provided with a downwardly-projecting pivot bolt, a socket piece engaging said pivot bolt, a worm journaled in said yoke and adapted to engage said worm teeth, with means for throwing 130

said worm into and out of engagement with said worm teeth, when desired, and a tripod provided with a housing engaging said pivot bolt, and having legs adjustably hinged to 5 said housing, substantially as described.

8. The combination with the gun and a supporting member rigidly attached thereto, and provided with worm teeth, of a yoke hinged to said supporting member and provided with a worm adapted to engage said worm teeth and to be thrown out of engagement therewith if desired, a pivot bolt projecting downwardly from said yoke, and a tripod provided with a housing having three 10 downwardly-projecting flanges with toothed segments at the base of said flanges, and with hollow tubular legs pivoted to said flanges, and spring-impressed latches mounted in said legs and adapted to engage said 15 segments, substantially as described.

9. In a gun of the character described, the combination with the gun, of a downwardly-projecting supporting member carried by the receiver and provided with a segmental rack having worm teeth, a yoke pivoted to said segmental rack, and provided with a downwardly-projecting pivot bolt, a socket piece engaging said pivot bolt, a worm journaled in said yoke and adapted 25 to engage said worm teeth, with means for throwing said worm into and out of engagement with said worm teeth, when desired, and a tripod provided with a housing having three downwardly-projecting flanges 30 with toothed segments at the base of said flanges, and with hollow tubular legs pivoted to said flanges, and spring-impressed latches mounted in said legs and adapted to engage said segments, substantially as de- 35 scribed.

10. The combination with the gun and a supporting member rigidly attached thereto, and provided with worm teeth, of a yoke hinged to said supporting member and provided with a worm adapted to engage said worm teeth and to be thrown out of engagement therewith if desired, a pivot bolt projecting downwardly from said yoke, a socket piece engaging said pivot bolt, and a 45 collapsible carriage engaging and supporting said socket piece, substantially as described.

11. The combination with the gun, of a downwardly-projecting supporting member carried by said gun and provided with a segmental rack having worm teeth, a yoke pivoted to said segmental rack, and provided with a downwardly-projecting pivot bolt, a socket piece for engaging said pivot bolt, a worm journaled in said yoke and adapted 55 to engage said worm teeth, with means for throwing said worm into and out of engagement with said worm teeth, when desired, and a collapsible carriage engaging and sup- 60

porting said socket piece, substantially as described.

12. In a gun of the character described, the combination with the gun, of a downwardly-projecting supporting member carried by the gun, a yoke pivoted to said supporting member and provided with a downwardly-projecting pivot bolt, a socket piece engaging said pivot bolt, and a tripod engaging said pivot bolt provided with a housing having three downwardly-projecting flanges with toothed segments at the base of said flanges, and with hollow tubular legs pivoted to said flanges, and spring-impressed latches mounted in said legs and adapted to engage said segments, substantially as described.

13. The combination with the gun, of a downwardly-projecting supporting member carried by said gun, a yoke pivoted to said supporting member, and provided with a downwardly-projecting pivot bolt, a socket piece engaging said pivot bolt, and a collapsible carriage comprising a central trail piece provided with an eye adapted to engage said socket piece, wheels, and link members connecting said trail piece with said wheels, substantially as described.

14. The combination with the gun and a supporting member rigidly attached thereto, of a yoke hinged to said supporting member, a pivot bolt projecting downwardly from said yoke, a socket piece engaging said pivot bolt, a tripod engaging said pivot bolt provided with a housing having three downwardly-projecting flanges with toothed segments at the base of said flanges, and with hollow tubular legs pivoted to said flanges, and spring-impressed latches mounted in said legs and adapted to engage said segments, and a collapsible carriage engaging 100 and supporting said socket piece, substantially as described.

15. The combination with the gun, of a downwardly-projecting supporting member carried by said gun, a yoke pivoted to said supporting member, and provided with a downwardly-projecting pivot bolt, a socket piece engaging said pivot bolt, a tripod engaging said pivot bolt provided with a housing having three downwardly-projecting flanges with toothed segments at the base of said flanges, and with hollow tubular legs pivoted to said flanges, and spring-impressed latches mounted in said legs and adapted to engage said segments, and a collapsible carriage comprising a central trail piece provided with an eye adapted to engage said socket piece, wheels, and link members connecting said trail piece with said wheels, substantially as described.

16. The combination with the gun, of a downwardly-projecting supporting member carried by said gun, a yoke pivoted to said

supporting member, and provided with a downwardly-projecting pivot bolt, a socket piece engaging said pivot bolt, a spring catch holding said pivot bolt in said socket piece, and a collapsible carriage comprising a central trail piece provided with an eye adapted to engage said socket piece, wheels,

and link members connecting said trail piece with said wheels, substantially as described.

In testimony whereof, I affix my signature.

ALEXANDER MICLAUS, JR.

Witness:

PETER GLIGOR.
